[57] CLAIM

The ornamental design for a combined dimmer control and face plate, as shown and described.

DESCRIPTION

FIG. 1 is a front elevational view of a combined dimmer control and face plate showing our new design, the rear being unornamented;

FIG. 2 is a right side elevational view thereof, the left side being a mirror image;

FIG. 3 is a bottom plan view thereof, the top being a mirror image;

FIG. 4 is isometric perspective view thereof;

FIG. 5 is a front elevational view of the second embodiment of the design of FIG. 1, the rear being unornamented;

FIG. 6 is a right side elevational view of FIG. 5, the left side being a mirror image;

FIG. 7 is a bottom plan view of FIG. 5, the top being a mirror image; and,

FIG. 8 is an isometric perspective view of FIG. 5. The broken line showing of a switch housing in FIGS. 2—4 and 6—8 is for illustrative purposes only.
